[57] CLAIM

The ornamental design for a front panel for a casement
window air conditioner, as shown and described.

DESCRIPTION

FIG. 1 is a perspective view of a front panel for a casement
window air conditioner, showing my new design;

FIG. 2 is a front elevational view thereof;

FIG. 3 is a right side elevational view thereof; the left side
elevational view being a mirror image; and,

FIG. 4 is a top view thereof; the bottom view being a mirror
image.
